UNITED STATES PATENT OFFICE

ALBERT E. ROBINSON, OF CINCINNATI, AND WILLIAM G. HOELSCHER, OF NORWOOD, OHIO, ASSIGNORS TO THE AMERICAN TOOL WORKS COMPANY, OF CINCINNATI, OHIO, A CORPORATION OF OHIO

LAPPING MACHINE

Application filed July 2, 1932. Serial No. 620,602.

Our invention relates to lapping machines for lapping meshing gears, and has for its object the provision of novel means for qualifying lapping engagement between the teeth of gears being lapped.

It is the object of our invention further to provide novel means for adjusting the angular relations between rotative members in the train of mechanism between gears; and, further, to provide resilient driving means between said rotative members.

It is the object of our invention further to provide novel means for adjusting the force of angular impact in both directions between meshing gears being lapped, whereby to impose forceful contact between the respective sides of the teeth of the meshing gears; further, to provide novel means for causing resilience of engagement between the respective sides of the teeth of meshing gears being lapped; and, further, to provide novel means whereby a preload is imposed between meshing gears being lapped.

The invention will be further readily understood from the following description and claims, and from the drawings, in which latter:

Fig. 1 is a plan view of my improved device.

Fig. 2 is an end elevation of the same.

Fig. 3 is an axial section of the qualifying head, taken on a vertical plane through Fig. 7; and partly broken away.

Fig. 4 is a plan view of the gage for the head, laid out in plane, and partly broken away.

Fig. 5 is a horizontal axial section of my improved device, taken on the line 5—5 of Fig. 2.

Fig. 6 is a side elevation of the same, partly broken away, and partly in vertical section on the line 6—6 of Fig. 1.

Fig. 7 is a cross-section of a detail of my improved device, taken in the plane of the line 7—7 of Fig. 5.

Fig. 8 is a cross-section of the same, taken in the plane of the irregular line 8—8 of Fig. 5.

Fig. 9 is a cross-section of the same, taken in the plane of the line 9—9 of Fig. 7; and,

Fig. 10 is a cross-section of a detail of the same, taken in the plane of the irregular line 10—10 of Fig. 7.

The present invention is an elaboration of the inventions shown, described and claimed in the copending applications for Letters Patent on improvements in lapping machines, filed in the United States Patent Office by Albert E. Robinson, one of the joint applicants herein, April 13, 1931, as Serial No. 529,735, 55 and Serial No. 529,736. 60

The machine comprises a frame 11, which supports an electric motor 12, which is preferably a reversible motor. A housing 13 is preferably fixed to the frame, as by bolts 14. 65 This housing has a drive shaft 15 therein, extending lengthwise of the frame, and journaled in bearings 16. A pulley 17 is fixed to this drive shaft, a belt 18 being received thereover and over a pulley 19 on the motor 70 shaft 20.

An arbor 21 extends crosswise of the frame and is rotatable in bearings 22, 23, in the housing (Fig. 5). It is exemplified as comprising a sleeve 25 provided with a bore 26 having a tapered end forming a socket 27, receiving the tapered end 28 of a spindle 29. A screw rod 31 is in the bore and has threaded connection 32 with the inner end of the spindle, and a head 33 received against the 80 end of the sleeve, for drawing the tapered end of the spindle into its tapered socket and fixing the spindle axially in the sleeve and permitting ready removal of the same.

Guideways 35 extend lengthwise of the 85 frame. A slide 36 is adjustable on said guideways toward and from the housing 13, accomplished by means of a screw-rod 37, journaled and held endwise in a bearing 38 at the end of the frame, and having threaded connection with a nut 39 fixed to the slide by a bolt 40, forming a micrometer adjustment for the slide (Fig. 6).

The slide supports an arbor 41, rotatable in bearings 42, 43, in a housing 44 on the slide. 95 This arbor comprises a sleeve 45 provided with a bore 46 having a tapered socket 47 at one end, in which the tapered end 48 of a spindle 49 is received. A screw-rod 50 has threaded connection 51 with the tapered end 100

of said spindle, and a head 52 received against the end of the sleeve. This arrangement draws the spindle firmly into the sleeve for centering the spindle and permitting its removal.

Master gears 55, 56, are received in meshing relation about one of the ends of the arbors, and gears to be lapped 57, 58, are received in meshing relation over spindles at the other 10 of the ends of said arbors. The gears rotate with their respective arbors, and are centered in suitable manner about their respective arbors.

Thus the master gear 55 is received about a 15 hub 61 and has key connection 62 with said hub so as to rotate therewith (Fig. 5). The hub is provided with an annular shoulder 63, a washer 64 being located between said annular shoulder and the gear 55. A washer 65 20 is received at the outside of the gear, a nut 66 being threaded over the threaded end 67 of the hub for clamping the master gear to the hub. Hubs of different diameters may be employed for master gears having different 25 sized holes, or filling sleeves may be employed for centering the gear upon the hub.

The master gear 56 is received about a bushing 71 on the sleeve of the arbor 41. The bushing is provided with a flange 72. The 30 bushing has key connection 73 with the sleeve of the arbor, and the gear has key connection 74 with the bushing. A washer 75 is received about the sleeve at the outer end of the bushing, a nut 76 being threaded over the threaded end 77 of said sleeve for clamping the parts toward an annular shoulder 78 on the 35 sleeve and clamping the parts to the sleeve. Bushings of different diameters may be provided for gears having holes of different diameters. Spindles 29, 49 having gear supporting portions of different diameters may be employed. The gear to be lapped 57 has key connection 79 with the spindle 29, and the gear to be lapped 58 has key connection 80 with the spindle 49. Bushings similar to the bushing 71 may be received about the hub 61 and the spindles 29, 49, for accommodating 40 gears having holes of different diameters.

Filling collars 81, 82, of different lengths 45 are received over the respective spindles, washers 83, 84, being at the outer ends of said respective sets of collars, and nuts 85, 86, are threaded to the outer ends of the respective spindles for clamping the gears to be lapped and the collars between flanges 87, 88, on the respective spindles and said nuts and washers. A plurality of gears to be lapped may be located side by side on the respective spindles.

50 A bevel gear 91 is fixed to the drive shaft 15 (Fig. 5). This bevel gear meshes with a bevel gear 92 mounted about the sleeve 25, the bevel gear having key connection 93 with the sleeve. The bearings 22, 23, are shown as ball bearings, the outer raceways of which

are received in annular rabbets 94, 95, in the housing 13, being clamped in place by caps 96, 97, fixed to the outer ends of said housing.

The inner raceways of these ball bearings are received about the outer circumference 70 of the sleeve 25. The outer end of the inner raceway of the ball bearing 23 is received against a shoulder 98 on the sleeve. The inner raceways of the ball bearings 22, 23, are held in spaced relation by the bevel gear 92 and 75 a collar 99. A collar 100 is received about said sleeve at the outer end of the inner raceway of the ball bearing 22, a nut 101 being threaded over the sleeve for clamping the collars and the inner raceways toward 80 the shoulder 98.

The arbor 41 is rotatable in the bearings 42, 43, the outer raceways of said bearings being located in annular rabbets 105, 106, in the housing 44, caps 107, 108 being secured 85 to said housing and clamped against said outer raceways.

A gear 110 is located about the sleeve 45, and has key connection 111 therewith. The inner raceways of the ball bearings 42, 43, are 90 spaced apart by means of said gear and a collar 112. A collar 113 is at the outside of the inner raceway of the ball bearing 42, a nut 114 being threaded over the threaded portion 115 of said sleeve for clamping said last-named collars, inner raceways and gear toward an annular shoulder 116 of said sleeve.

Lubricant shields 117, 118, are received about the sleeves 25, 45, between shoulders 119, 120 thereon and the respective gears to 105 be meshed.

Endwise reciprocation may be imparted to the arbor 41 for causing endwise movement between the respective gears of the sets of gears, so as to cause lapping action between 105 the teeth of the gears being lapped across the widths of said teeth (Figs. 1, 2, 5 and 6). For this purpose the housing 44 is mounted on a cross slide 125 on the slide 36. The slide 36 is provided with a guide 126 with which a 110 guideway 127 on the cross slide coacts.

The housing 44 is provided with bearings 131, 132, 133, in which shafts 134, 135, 136 rotate. The shaft 134 has a bevel pinion 137 thereon which meshes with the bevel gear 110. The shaft 134 is also provided with a pinion 138. The shaft 135 is provided with a gear 139 meshing with the pinion 138, and with a pinion 140 which meshes with a gear 141 on the shaft 136. The shaft 136 is provided with a crank 142.

A bearing 145 of a link 146 is received about said crank at one end of said link. The other end of said link has a bearing 147 about a pin 148 in a stand 149 fixed to the slide 36. This construction converts the rotary motion of the crank into reciprocating linear movements of the cross slide and imparts endwise movements to the arbor 41 and the gears mounted thereon.

Means are provided for adjusting the angular relations between the gears being lapped on the respective arbors, and means are also provided for causing resilient coaction between the faces of the teeth of the respective gears being lapped, and these respective means are shown so arranged that angular adjustments may be effected toward the respective sides of similar radial planes of the gears being lapped, and that resiliently yielding lapping contacts may be made between the respective sides of the teeth of the meshing gears being lapped.

A head 151 is provided for effecting these operations (Figs. 3 and 5). The head comprises the relatively movable sections 152, 153, one of which is fixed with relation to one of the master gears and the other of which is fixed with relation to one of the gears being lapped. There are resiliently yielding means between the two sections for permitting resilient yielding between the gears being lapped, and one of the sections is also provided with adjusting means for causing preponderance of pressure at the respective sides of the teeth of the gears being lapped. These latter adjusting means are shown on the section 152.

More particularly described the section 152 comprises an outer member 154, shown as a ring or plate, in which the hub 61 is located, the hub being extended outwardly to form a support for the master gear 55. The hub is centered and is held endwise on a reduced end 155 of the sleeve of the arbor 21.

The hub is provided with a worm wheel 161 with which a worm 162 meshes (Figs. 3 and 8). This worm is on a worm shaft 163, journaled in bearings 164, 165, of the outer ring portion 154 of the section 152 which surrounds the worm wheel. The worm shaft is held endwise in said bearings by an annular shoulder 166 and a washer 167 and nut 168 threaded over the threaded end of the worm shaft, and located at the respective ends of the bearing 165. The worm shaft is provided with suitable formation for rotating the same, shown as a square head 169 for receiving a suitable wrench.

The head and the washer and nut are respectively in recesses 170, 171, in said outer ring or member. Adjustment of the worm shaft adjusts the angular relation of the hub 61 on which the worm wheel is located and the ring member or outer portion of the section 152 on which the worm is located. The adjusting means adjusts the angular relation of the gear to be lapped and its arbor with relation to the master gear 55.

The section 153 comprises a housing 175 mounted on a step 176 of the arbor between shoulders 177, 178 on said arbor, locating the housing between the shoulder 178 and the section 152 in such manner that relative ro-

sections 153, 152. The housing has key connection 179 with the arbor.

The housing is provided with an annular chamber 181 which is closed by an end plate 182 positioned by annular shoulders 183, 184, 70 in the respective annular walls of said chamber. Said cover and the bottom wall of the chamber are respectively provided with arcuate slots 185, 186, through which bolts 187, 188 are received into threaded holes 189, 190 75 in the outer ring member 154 of the section 152. The bolts are arranged to be threaded into their threaded holes to sufficient extent to hold the parts in axial directions and at the same time permit relative rotations between the sections 152, 153. The bolts are preferably clamped in adjusted positions by plugs 191 received in threaded holes 192 in the outer member 154 and clamped against the respective bolts by screws 193 in said respective threaded holes.

Levers 195, 196, are pivoted on pivot pins 197, 198, shown as shoulder pins whose ends are located in holes in the respective walls of the chamber 181, said levers being provided with toes 199, 200, which are arranged to bear against the bolt 187 (Figs. 7, 9 and 10). The levers are urged toward said bolt by springs 201, 202 received about rods 203, 204 having rounded heads 205, 206 received in seats 207, 208 in the heels 209, 210 of said levers. Bearings 215, 216 have pin journals 217, 218 journaled in holes in the respective walls of the chamber 181, and are provided with slide holes 219, 220 in which the rods 100 203, 204 have axial movements.

In operation, rotation is imparted to the drive shaft. This rotation may be in either direction or alternately in opposite directions, as may be desired or the character of 105 the work requires. The master gears 55, 56, are provided with teeth of proper form, pitch and depth for determining the form, pitch and depth of the teeth of the gears to be lapped by the lapping operation.

The gears to be lapped usually have their teeth cut or formed slightly oversize and are then hardened. The hardening of the gears is likely to cause change in the form of the gears or some or all of the teeth, and the 115 object of the lapping is to reduce and reshape the teeth to their proper forms and sizes. The hardened gears may also have high spots on their teeth, or the teeth or parts of the same may be warped or their surfaces be 120 rough or uneven, these objectionable conditions being corrected by the lapping.

The lapping is performed by causing meshing relation between the rotating gears being lapped and supplying a lapping compound, 125 which may be a mixture of powdered carborundum and grease, either manually or automatically to their teeth in suitable manner.

When uneven or untrue parts of the teeth 130

being lapped engage each other in the lapping operation, a momentary excess resilient resistance takes place between the gears for aiding in more quickly reducing such uneven 5 or untrue parts.

Our improved device provides means whereby pressure or a preload is exerted between the engaging faces or proximate sides of the teeth of the gears being lapped, for 10 speedily reducing said engaging faces or proximate sides to desired form and size, and whereby such pressure is exerted selectively toward the respective sides of the respective teeth in order to reduce both sides of all 15 of the teeth to desired form and size, and whereby such pressure or preload is varied according to the sizes of the teeth of the gears being lapped, so as to expedite the lapping.

Assuming that the gears being lapped have been adjusted toward each other to full extent permitted by the unlapped condition of their teeth, rotation of the worm 162 in one or the other direction causes rotation of 20 the outer member or ring 154 of the section 152 of the head 151 with relation to the inner member or hub 61 of said section 152, and causes planetary shifting of the bolt or contact member 187, which reacts upon the respective levers 195, 196, causing compression of the spring acting on that lever toward which said bolt or contact member has been moved, and thereby causes preponderant pressure, or, it may be termed, a preload, 25 upon the coacting sides of the teeth of the gears being lapped which by said adjustment have been urged into more intimate contact.

The adjustments between the outer member 154 of the section 152 and the section 153 30 of the head 151 are preferably made to definite extents, dependent on the sizes of the teeth of the gears, the extent of adjustment increasing with said sizes, for instance in accordance with the graduations 221, 222 of a 35 scale 223. These graduations are placed on two of the relatively shiftable parts of the head 151, being shown on the outer peripheries of the respective sections 152, 153.

The graduations at the respective sides of 40 the zero lines indicate desired relations between the shiftable parts of the head when opposite faces of gears having teeth of different diametral pitches are being lapped. The lines denoting corresponding diametral 45 pitches in the respective graduations on the respective sections of the head are brought in line with each other in this adjustment, it being assumed that the gears being lapped have been adjusted toward each other to 50 full extent.

Thus when lapping gears having teeth of five diametral pitch, the lines of the numerals 5 at one side of zero are brought in line with each other, and when lapping gears 55 having teeth of sixteen diametral pitch, the

lines of the numerals 16 in the respective graduations at one side of zero are brought in line with each other.

The markings of the graduations are repeated at opposite sides of the zero lines in 70 reverse order, indicating an advanced relation in each direction between the anchor member or bolt 187 and the respective levers 195, 196, indicating an abnormal pressure or preload in one direction or in the other 75 upon the teeth of the gears being lapped, reversals in directions of rotations of the gears being also caused when graduations at opposite sides of the zero lines are used.

The gears on the arbor 41 are fed toward 80 the gears on the arbor 21, during the lapping operation, by adjustment of the slide 36 by means of the micrometer screw 37. The lapping is preferably continued until the full depth and form of the teeth being lapped is 85 obtained.

Having thus fully described our invention, what we claim as new, and desire to secure by Letters Patent, is:

1. In a gear lapping machine, the combination of a pair of arbors, means for mounting meshing master gears about the axes of rotation of said arbors, means for mounting meshing gears to be lapped about the axes of rotation of said arbors, arranged to form 90 rotative connections between said gears including a pair of rotative members, means for adjusting the angular relations between said rotative members, and resilient resistant means acting on the latter.

2. In a gear lapping machine, the combination of meshing master gears, meshing gears to be lapped, and driving means between said gears including resilient means, coacting rotative members, and means for adjusting the angular relations between said coacting rotative members resisted by said 105 resilient means.

3. In a gear lapping machine, the combination of meshing master gears, meshing 110 gears to be lapped, and driving means between said gears including resilient means, coacting rotative members, means for adjusting the angular relations between said coacting rotative members resisted by said 115 resilient means, and means determining the extents of said adjustments according to the diametral pitches of the teeth of said gears.

4. In a gear lapping machine, the combination of meshing master gears, meshing 120 gears to be lapped, rotative mounting means for said gears, rotative members between said mounting means, oppositely acting resilient means between said rotative members, anchoring means on said respective rotative 125 members for said resilient means, and means for adjusting the angular relation between said anchoring means.

5. In a preloading device for lapping machines of the character described, the combi- 130

nation of a mounting for a master gear, a mounting for a gear to be lapped, an anchor member between said mountings, said anchor member comprising an anchor, means for adjusting the angular relation between said anchor member and one of said mountings, and spring means between said anchor and the other of said mountings.

6. In a gear lapping machine of the character described, the combination with meshing master gears and meshing gears to be lapped, of a mounting for a master gear and a mounting for a gear to be lapped, comprising a plurality of rotative members, one of which is angularly held with relation to said master gear and the other of which is angularly held with relation to said gear to be lapped, a third rotative member, angular adjusting means between said third rotative member and one of said first-named rotative members, and spring resistance means between said third rotative member and the other of said first-named rotative members.

7. In a preloading device of the character described, the combination of a pair of gear mountings, an anchor therebetween, means for angularly adjusting said anchor with relation to one of said gear mountings, and resistant spring means between said anchor and the other of said gear mountings.

8. In a preloading device of the character described, the combination of a pair of gear mountings, an anchor and spring resistant means therefor forming oppositely urging parts between said gear mountings, supports for said parts, and means for angularly adjusting one of said supports with relation to one of said gear mountings.

9. In a preloading device of the character described, the combination of a pair of gear mountings, an anchor and spring resistant means therefor forming oppositely urging parts between said gear mountings, supports for said parts, means for angularly adjusting one of said supports with relation to one of said gear mountings and means determining the extents of said angular adjustments according to the diametral pitches of the teeth of the gears.

50 10. In a preloading device of the character

ter described, the combination of a pair of gear mountings, a preloading head therebetween comprising a pair of rotative members, one for each of said mountings, an intermediate rotative member, means for angularly adjusting said intermediate rotative member with relation to one of said pair of rotative members, an anchor on one of said last-named members, and oppositely acting parts coacting with said anchor and spring means therefor on the other of said last-named members.

70 11. In a preloading device of the character described, the combination of a pair of gear mountings and a preloading head therebetween comprising three relatively rotary members two of which are anchored to said respective gear mountings and the third of which has adjusting connection and coactive rotary resilient connection respectively with said two of said members.

75 12. In a preloading device of the character described, the combination of a pair of gear mountings and a preloading head therebetween comprising rotative members, an anchor on one of said rotative members, oppositely acting levers acting oppositely on said anchor, said levers pivoted to another of said rotative members, spring means on said other of said rotative members resistingly acting on said levers, and angular adjusting means between one of said last-named rotative members and a third one of said rotative members.

80 13. In a preloading device of the character described, the combination of a pair of gear mountings, a preloading head therebetween comprising a housing, oppositely presented levers pivoted in said housing, springs in said housing acting resistingly on said respective levers, an anchor between said levers, said levers and said anchor forming oppositely resistant members, and angular adjusting means between one of said oppositely resistant members and said housing.

85 In testimony whereof, we have hereunto signed our names.

ALBERT E. ROBINSON.

WILLIAM G. HOELSCHER.
